UNITED STATES PATENT OFFICE

101,532

DESIGN FOR A WELDING ELECTRODE EXTRUDING MACHINE

Claude J. Hol slag, South Orange, N. J.

Application June 6, 1935, Serial No. 57,160

Term of patent 14 years

To all whom it may concern:

Be it known that I, Claude J. Hol slag, a citizen of the United States, residing at South Orange, in the county of Essex, State of New Jersey, have invented a new, original, and ornamental Design for a Welding Electrode Extruding Machine, of which the following is a description, reference being had to the accompanying drawings forming a part thereof.

In the drawings:

Figure 1 is a perspective view of one side of the machine.

Figure 2 is an end view of the machine looking from right to left of Figure 1.

I claim:

The ornamental design for a welding electrode extruding machine, as shown.

CLAUDE J. HOLSLAG,
